UNITED STATES PATENT OFFICE.

JOHN MAURICE POWELL, OF STOCKTON, UTAH.

RAILROAD-SWITCH.

No. 802,236.

Specification of Letters Patent.

Patented Oct. 17, 1905.

Application filed May 11, 1905. Serial No. 259,923.

To all whom it may concern:

Be it known that I, JOHN MAURICE POWELL, a citizen of the United States, and a resident of Stockton, in the county of Tooele and State of Utah, have invented a new and Improved Railroad-Switch, of which the following is a full, clear, and exact description.

The purpose of my invention is to provide a railroad-switch of exceedingly simple, durable, and economic construction which can be operated with the least possible trouble and which is not liable to become clogged in wintry weather and is also not liable to get out of order.

Another purpose of the invention is to provide a construction of switch which dispenses with frogs and guard-rails and to provide very simple and effective means for mounting and operating the switch-rail, which rail is practically a section of the main line.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of a portion of the main line and siding and the improved switch applied, a portion of the covering for the switch-operating mechanism being broken away and the switch being shown set for the main line in full lines and as thrown for the siding in dotted lines. Fig. 2 is a longitudinal section taken practically on the line 2 2 of Fig. 1, and Fig. 3 is a transverse section taken substantially on the line 3 3 of Fig. 1.

A and A' represent the rails of the main line, and B and B' the rails of the siding. Adjacent to where the inner rail B of the siding and the inner rail A' of the main line converge a turn-table C is located, which turn-table in its detail is best shown in Fig. 3.

This turn-table or pivoted saddle consists of a bed-piece 10, which is countersunk in a tie 11 to such an extent that its upper face is flush with the upper face of the tie, and in said bed-piece 10 a circular chamber 12 is formed open at the top. In this chamber 12 a circular plate 13 is mounted to turn. This revoluble plate is prevented from leaving the said chamber 12 by securing cover-plates 14 at the upper portion of the bed-piece 10, which cover-plates extend over the revoluble plate 13. The opposing edges of the cover-plates 14 are in-

clined in opposite directions from a point at or near their centers, so as to produce between them an opening 15, which is widest at its outer portions and is narrowest at its central portion, as is best shown in Fig. 1.

The heel portion of the switch-rail D is made to enter the opening 15 and to extend across the revoluble plate 13 of the turn-table or pivoted saddle and is secured to said revoluble plate 13 by means of bolts 16 or their equivalents. The heel portion of the switch-rail D is opposite and adjacent to the inner-rail A' of the main line where the said rail is broken for the junction of the siding, and the free end d of the switch-rail D is beveled upon both sides so as to fit snugly to a rail of the main line with which it is adapted to engage when set for the main line or set for the siding. The switch-rail D is practically a section of the inner rail A' of the main line.

A cover-plate 17 is laid over the ties and suitably secured thereto from a point adjacent to the turn-table or pivoted saddle C to a point on the main line somewhat in advance of the switch-target E, employed in connection with the switch. This cover-plate 17 is provided with a curved transverse slot 18, as is best shown in Fig. 1, and the switch-rail D has play over the upper face of the said cover-plate 17.

The switch-rail D is operated as follows: A lever 19 is pivoted at one end to the switch-rail D at a point between its center and its free end, the pivot-pin extending up through the slot 18, and the pivot-pin 21 of the lever 19 is located between its center and its free end, and at the free end of the lever 19 an elongated metal loop 20 is provided, as is best shown in Fig. 1. In connection with the lever 19 a second lever 22 is pivoted at one end to a convenient tie, as is shown at 23 in Figs. 1 and 2, and the opposite end of this second lever 22 is provided with a pin 24, which extends down loosely into the elongated loop 20 of the lever 19. This second lever 22 is connected with the switch-target by a connecting-bar 24^a of any approved type.

It will be observed from the character of the switch described and the operating mechanism connected with it that the switch-rail can be thrown quickly and with comparative ease, a slight movement at the switch-target producing quite an extended movement of the switch-rail. It will also be observed that all of the operative parts provided for the switch-rail D are fully protected.

It may be here remarked that where the

lever 19 connects with the switch-rail D a slot 25 is made and the connecting-pin 26 is loosely passed through said slot into the switch-rail D, as is shown in Fig. 2.

5 Having thus described my invention, I claim as new and desire to secure by Letters Patent—

1. In railroad-switches, the combination with the rails of the main line and the rails of a siding, of a switch-rail constituting substantially a section of a rail of the main line, a turn-table to which the heel end of the switch-rail is secured, said turn-table comprising a bed-piece, a revoluble plate mounted in the bed-piece, and cover-plates securing 15 the revoluble plate in the bed-piece, and means for shifting the said switch-rail.

2. In railroad-switches, the combination with the rails of the main line and the rails of a siding, of a turn-table or pivoted saddle 20 located adjacent to the junction of the inner rails of the siding and the main line, which turn-table or pivoted saddle consists of a bed-piece, a plate mounted to turn in the bed-piece, and cover-plates which are secured to the bed-

25 piece and extend over the rotary member, the said cover-plates having an angular opening between them, a switch-rail constituting a portion of the inner rail of the main line, one end of said switch-rail being secured to the 30 rotary member of the turn-table or pivoted saddle, the other end of the said switch-rail being beveled upon both sides, a lever fulcrumed between its center and one end, which lever at its longer end is attached to 35 the said switch-rail, being provided at its shorter end with an elongated slot, a second lever pivoted at one of its ends and having sliding connection at its opposite end with the first-named lever, a switch-target, and a 40 connection between said target and the lever which is fulcrumed at one end.

3. In railroad-switches, the combination with the rails of the main line and the rails of a siding, of a turn-table or pivoted saddle 45 located in front of the inner rails of the main line and siding where they converge, said turn-table or pivoted saddle consisting of a bed-piece provided with a circular chamber

open at the top, a circular member mounted to turn in the said chamber, and cover-plates 50 secured to the bed-piece and extending over the said revoluble member, a space intervening the inner edges of the said cover-plates, the inner edges of the cover-plates being inclined in opposite directions from a central 55 point, a switch-rail constituting a continuation of the inner rail of the main line, which switch-rail is secured to the revoluble member of the turn-table or pivoted saddle within the space between the cover-plates of said 60 turn-table, a lever fulcrumed between its center and one end, the longer end of which lever is secured to the said switch-rail, the shorter end of the lever being provided with an elongated opening, a second lever pivoted 65 at its end, being provided with a pin at its opposite end which extends down through the slot in the first-named lever, a switch-target, and a bar connecting the said switch-target with the central portion of the lever which is 70 pivoted at the end portion, substantially as described.

4. In railroad-switches, the combination with the rails of the main line, one of said rails having a pivoted section forming a switch-rail, and the rails of a siding, of cover-plate 75 extending over the ties and upon which the switch-rail moves, and means arranged below the cover-plate for operating the switch-rail.

5. In railroad-switches, the combination with the rails of the main line and siding, and a pivoted switch-rail, of a cover-plate secured upon the ties and upon which the switch-rail moves, said plate being provided with a curved 80 transverse slot, a lever pivoted between its ends and having one end pivoted to the switch-rail, the pivot projecting through the slot of the cover-plate, and means for operating said lever.

In testimony whereof I have signed my name 90 to this specification in the presence of two subscribing witnesses.

JOHN MAURICE POWELL.
